(57) **CLAIM**

The ornamental design for a powder inhalator, as shown and described.

DESCRIPTION

FIG. 1 is a front elevational view of a powder inhalator showing our new design with a cap in a stored position;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a perspective view thereof;
FIG. 8 is a front elevational view of the powder inhalator of FIG. 1 with the cap removed;
FIG. 9 is a rear elevational view of FIG. 8;
FIG. 10 is a left side elevational view of FIG. 8;
FIG. 11 is a right side elevational view of FIG. 8;
FIG. 12 is a top plan view of FIG. 8, the bottom plan view thereof being identical to FIG. 6;
FIG. 13 is a front elevational view of the powder inhalator of FIG. 8 with an operating unit on the bottom of the inhalator depressed; and,
FIG. 14 is an exploded front elevational view of the power inhalator of FIGS. 1 and 8.
